Application March 30, 1934, Serial No. 718,119

20 Claims. (Cl. 197—84)

This invention relates to the printing or impressing of letters or other characters, and more particularly to typewriters, and the like, or mechanisms, or attachments therefor whereby controlled spacing of the imprinting characters is effected to produce justified lines.

One of the principal objects of the invention is the provision of a typewriter, or the like, for reassociating the type characters of unjustified copy into lines of justified length wherein the characters are equally spaced, and having provision for effecting justification into lines of different predetermined length.

Another object of the invention is the provision of such a typewriting device having a character spacing mechanism of simple construction movable by steps and including an adjustably variable member for determining the length of a step and mechanism associated therewith for establishing an adjusted positioning of the spacing mechanism that is coordinated with the number of characters in an unjustified line for reproduction of that line to justified length.

Another object of the invention is the provision of a justifying typewriter having a single control that is movable in one path of travel for adjusting the character spacing and is movable in another path of travel for alteration of the justified line length.

Other objects and advantages of the invention will be apparent from the following description, the accompanying drawing and the appended claims.

Cross-reference is made to my earlier filed and co-pending application for imprinting apparatus, Serial No. 669,097, filed May 3, 1933.

In the drawings, which disclose a preferred embodiment of the invention,—

Fig. 1 is a side elevational view of a typewriting device constructed in accordance with the present invention;

Fig. 2 is an enlarged fragmentary plan view of Fig. 1;

Fig. 3 is a vertical sectional view as indicated by the line 3—3 of Fig. 2;

Fig. 4 is a fragmentary vertical sectional view as indicated by the line 4—4 of Fig. 2;

Fig. 5 is a diagrammatic showing of a portion of the space controlling mechanism; and

Fig. 6 is a view similar to Fig. 5 showing another portion of the space controlling mechanism.

The drawings, in which like characters of reference designate like parts throughout the several views thereof, illustrate a typewriting de-

vice comprising a frame 10 upon which is mounted a movable carriage 11 that serves as support for a platen 12 upon which type characters are adapted to be associated. The typewriter has the usual keyboard 14 and has type bars which are controlled by actuation of the various keys for association of the characters on the platen. As the type bars and associated mechanism may be of well known form it is thought that illustration or further description of these parts is unnecessary to a clear understanding of the invention. The type bars are arranged to strike the platen at the position of the guide member 15 which, as shown, also serves as a support for a ribbon 16.

The carriage 11 is mounted for movement on the frame 10. As shown, the frame 10 has a track 20 which extends in the direction of platen travel and is provided with a groove 21 within which are spaced bearing balls 22 that support a similar ball groove 23 that forms part of the carriage 11. Additional support is afforded by a cross bar 25 suitably mounted on a left hand bracket 26 and a right hand bracket 27 that extend from the frame 10. A yoke 28, fixed to the carriage 11, carries rollers 30 which engage the bar 25 and, with the bearing track, serve to support and guide the carriage.

The platen and carriage are urged to the left, that is, from the left hand margin position of writing toward the right hand margin position, by spring tension. The carriage is manually moved to the right, and is moved to the left by the spring upon release of an escapement. The movement to the left is in stepped amounts corresponding to character spaces. There is provision for varying the length of a step. As shown, a spring tensioned spool 32, which is supported from the frame structure at 33, has wrapped upon it a ribbon 34 which is attached to the right hand side of the carriage at 35 and by the tension of the spring, urges the carriage toward the left. The escapement mechanism, as shown, comprises a pinion 40 and an escapement wheel 41 which are assembled for free rotation on a stud 42 that is carried by a bracket extension 43 of the frame 10. The pinion and escapement wheel are operatively connected by an overrunning clutch in the form of a pawl 45 which permits the pinion 40 to move with respect to the escapement wheel 41 for free movement of the carriage and platen to the right, but which locks to prevent movement to the left. A rack bar 46 which is operatively connected to carriage 11 normally stands in meshing engagement with the pinion 40, and

an escapement release, indicated generally at 47, engages the escapement wheel and is mounted on the frame 10. The interconnection of these parts is such that the tension of the spring within the spool 32 is taken by the escapement release which holds the carriage against movement. As the various keys are actuated the escapement release is caused to rock and thus provide a stepped movement of the rack bar and associated carriage. As the escapement and release are of well known form, and these parts as well as suitable operating connections from the release to the type keys may be such as described in the patent to Hess et al. 1,427,464, August 29, 1922, it is thought that further illustration or description of this mechanism is unnecessary to a clear understanding of the invention.

It is to be noted that the escapement and release are of such character as to permit stepped movement of the rack bar in uniform amounts. As mentioned above, there is provision for varying the length of a step. By making such provision the number of character spaces in a line of predetermined length may be varied, and consequently lines having different numbers of characters may be re-associated to the same length. To accomplish this the rack bar 46 is mounted on the carriage in such a manner that it has a limited amount of movement with respect to the carriage and platen in the direction of carriage movement. Mechanism is incorporated between the rack bar and carriage which is adjustably variable and which may be controlled to provide a desired length of stepped movement of the carriage. In addition, the rack bar may move vertically with respect to the carriage an amount sufficient to disengage it from the escapement pinion 40 so that the carriage may be rapidly traversed to the left. As mentioned, rapid traverse to the right is permitted by the overrunning clutch.

In the illustrated embodiment of the invention the rack bar is shown to be carried by a control rack that is in turn supported by the carriage. As shown, the rack bar 46 is supported on a control rack 51 which has spaced projecting studs 52 carrying shoulder screws 53 that pass through vertical slots 54 in the rack bar. The slots and screws are so proportioned as to prevent any relative movement between the two racks in the direction of platen travel, and to permit some vertical movement of the rack 46. The vertical depth of the slots 54 is such that the rack may be lifted from engagement with the pinion 40 when it is desired to rapidly traverse the carriage to the left without actuating the space bar of the typewriter. This traversing movement is accomplished by actuating the rack bar release 50 which, as shown, comprises a shaft 55 which is journaled at opposite ends of the carriage and which has fixed to it sleeves 56 with laterally projecting fingers 57 that engage slots 58 in the rack bar. The slots are somewhat longer than the relative movement of the rack bar and carriage. A forwardly projecting operating handle 60 is also fixed to the shaft 55 so that upon downward movement of the handle 60 the rack bar 46 will be lifted. Downward movement of the handle is resisted by a spring 61 having connection at 62 to a projection on the carriage and at 63 to an arm on one of the sleeves 56.

The control rack 51 is supported on stud projections 65 on the carriage. Shoulder screws 66 pass through horizontal slots 67 in the control rack and engage the studs 65. The interengage-

ment of the screws 66 and slots 67 is such that the control rack may move with respect to the carriage in the direction of platen travel and is closely held in a direction perpendicular to this.

The relative movement of the control rack and the rack bar with respect to the typewriter carriage is controlled by a mechanism including an adjustably variable member 70, (Fig. 3) and by a connecting unit 71 comprising a stub shaft 72 journaled in a downwardly extending arm 73 of 10 the carriage and having rigidly attached adjacent its respective ends a segment 74 and a driving arm 77. The segment 74 is provided with teeth 75 which mesh with teeth 76 of the control rack 51 and the remote end of the driving arm 15 77 is operatively connected to the member 70.

The adjustably variable member is constructed as a lever having a pivotal support on the frame 10, and is provided with an operating mechanism whereby its angular positioning may be adjustably varied; that is, it can be moved to any point throughout its range of adjustment, and the spacing steps of the carriage are adjusted accordingly. As shown, the member 70 is provided with a bracket 80 having a hub portion 81 that is 25 engaged by a stud 82 which is fixed to a bracket 83 extending from the frame 10. The stud 82 serves as a pivot axis upon which the lever 70 may turn. The lever 70 has a slot 85 for engagement with the end of the arm 77. As shown, 30 the arm end carries a stud 87 upon which are mounted a roller 90 and spaced collars 91. The roller 90 is of a diameter to be closely received within the slot 85 and the collars 91 are of sufficiently larger diameter to overlie the sides of the 35 lever adjacent the slot and thus serve to hold the roller within the slot. The slot 85 which serves as a guideway for the roller 90 is a straight slot and is positioned so that the axis of the roller 90 will move in a line coinciding with the 40 pivotal axis of the member 70.

As the connecting unit 71 is supported from the carriage it will move with the carriage. Upon moving the carriage the roller 90 at the end of the arm 77 and engaged within the slot 85 will 45 move along the slot as the lever 70 is supported by the frame 10 and therefore is carried upon a fixed pivot. The relative movement of the carriage with respect to the racks is governed by the angular positioning of the adjustably variable 50 member or lever 70. When the lever stands so that the slot 85 is parallel to the direction of platen travel the carriage may move on the frame without any movement of the control rack and rack bar with respect to the carriage. The character space movement of the escapement imparted to the carriage when the lever is horizontal corresponds to the normal character spacing of the typewriter. That is, if the escapement is such as to provide ten character spaces per inch 60 of carriage travel the carriage will move in such amounts when the lever stands parallel to the direction of platen travel. If, however, the lever slot stands inclined with respect to the direction of platen travel there will be relative movement 65 between these parts which will slightly vary the amount of a step movement of the carriage with respect to the movement of the escapement. There is, therefore, a controllable mechanism between the rack bar and the carriage so that the 70 character space movement imparted by actuation of the escapement may be adjusted.

A control is provided for adjusting the stepped movement of the platen. This control includes a shaft 93 which is mounted for rotation in brack- 75

ets 94 that extend from the frame 10. A readily accessible control handle 95 is provided, and a pinion 96 is fixed to the shaft in intermeshing engagement with the teeth 97 which are cut in the end of the lever 10. The teeth 97 are cut on a radius centered on the pivot axis 82 of the lever. Rotation of the handle 95 and shaft 93 therefore serves to adjust the angular positioning of the lever 10. The interconnection between the control shaft and the lever 10 is thus such that the angular positioning of the lever may be adjustably varied any extent desired.

The angular movement provided in the lever 10 is sufficient to accommodate the maximum required justifying movement. That is, it will permit an adjustment of space length such as to enable a short unjustified line to be spread to the justified length. In practice it has been found that six space justification is sufficient for all practical purposes. To accomplish this necessitates movement of the lever 10 to an angular position such that when moving the carriage the distance of the predetermined line length the connecting member 11 will be actuated an amount 25 to cause a relative movement between the rack bar and the platen of six character spaces in the predetermined line length.

There is a definite angular positioning of the lever 10 at which any unjustified line should be spaced to reproduce it to justified length. Justified copy consists of lines of uniform length arranged with aligned margins. There is provision in this device for accurately maintaining both line length and margins. The line length is held to a predetermined figure by providing means in the control whereby the lever may be held in predetermined angular positions coordinated to the normal length of character space and the predetermined length of a writing line so that the character spacing may be accurately varied by definite amounts differing by whole character spaces in the predetermined or justified line length. This positioning means, which is more fully described below, includes a detent plate 45 having angularly spaced notches which are successively engaged by a spring tensioned detent member as the shaft 93 is rotated. The angular spacing of the detent notches is such that rotation of the control shaft between adjacent notches will vary the positioning of the lever 10 by an amount sufficient to alter the number of character spaces in a predetermined line length by one whole character space. For example, if the escapement mechanism is so proportioned to afford ten normal character spaces per inch of travel of the platen and a six inch justified line is established as the predetermined line length, there will then be 60 normal character spaces in the justified line length. This spacing 55 will exist when the lever 10 stands with the slot parallel to the direction of platen travel. As shown, the device is constructed so that the lever 10 may move in a clockwise direction from a normal position as viewed in Fig. 3. Assuming the lever 10 to be moved to an angular positioning, as the platen is moved from the left hand margin position (as shown in Fig. 3) to the right hand margin position the connecting member 11 will be given a clockwise movement which will move the control rack 51 and rack bar 46 to the right with respect to the carriage. This, in effect, moves the carriage to the left with respect to the rack bar and escapement and the character space movement per step of the escapement will therefore be greater than when the lever is in

its normal positioning. By increasing the angularity of the lever 10 the character space length is accordingly increased so that, for example, only 56 character spaces will occur in the predetermined line length which accommodates 60 normal spaces.

The control is arranged so that it not only will position the lever to provide character space lengths which are aliquot fractions of the predetermined line length but in addition incorporates 10 mechanism whereby the space length may be established by reference to characters arranged in unjustified lines as an index in setting the position of the lever 10 so that the proper length of character space movement of the carriage may be instantly and accurately determined. As shown, the frame 10 has upwardly extending brackets 100 which serve as a support for a copy carrier in the form of a roller 101 having operating handles 102. The roller affords a convenient 20 means of supporting unjustified copy for association into lines of justified length. Such copy, when inserted in the carrier, is held in place on the roller by provision of clips 103 that are slidably mounted upon a cross bar 104 attached at its 25 ends to the bracket 100.

An indicating pointer 106 extends upwardly toward the roller 101 and terminates in an end portion 107 that is adapted to register with an unjustified line end. The pointer is operatively 30 connected to the control shaft 93, as will be more fully explained, for movement by normal character spaces. The interconnection of the several parts on the control shaft provides a coordinated movement between the indicating pointer and the 35 lever 10 so that movement of the shaft 93 to bring the pointer into registration with any random line end automatically establishes an angular positioning of the lever such as to alter the character space length for reproduction of the indicated 40 unjustified line to the predetermined line length. As shown, the pointer 106 is affixed at its lower end to a bar 110 which extends across the machine and is supported from brackets 111 and 112 on the frame. Each bracket carries a shoulder screw 45 113 which engages a slot 114 in and extending lengthwise of the bar. A tensile spring 116, acting between a stud 117 on bracket 11, and a stud 118 on the bar, tends to urge the latter toward the left as viewed in Fig. 2. The left end of the 50 bar 110 carries a roller 119 which is adapted to selectively engage one of a series of cams carried by the shaft 93. As shown, the roller 119 engages a cam 120. This cam is shown diagrammatically 55 in Fig. 6 and has a series of angularly spaced stepped faces which differ in elevation by amounts equal to a normal character space length, and which are in angular extent coordinated to the lever positionings that will produce the different character space lengths. It is pointed out that the pointer registers with unjustified copy. This copy is written at uniform normal character spacing, and the cam is arranged so that the pointer will move by normal character space steps. The difference in elevation between adjacent cam 60 faces, therefore, corresponds to one normal space. As shown, the cam 120 has seven angularly spaced stepped faces so that upon rotation of the shaft 93 the pointer may move from a position corresponding to the predetermined line length to a 65 position six normal character spaces shorter than this.

As mentioned, the shaft 93 also carries positioning means in the form of a detent plate 121 which has angularly spaced notches 122 for successive 75

engagement by a detent member 123 that is mounted upon brackets 111 and 124. As shown, the detent member is carried by shoulder screws 125 which project through slots 126 in and extending lengthwise of the member 123. This member is constantly urged toward the left by a spring 127 that is supported on one end by a stud 128 fixed to the bracket 111, and at the opposite end by a stud 129 that is part of the member 123. The left hand end of the member 123 carries a roller 130 which engages the detent notches. As mentioned above, the detent notches are angularly spaced apart amounts such as to change the character spacing by one whole character space in the predetermined line length. They correspond in positioning to the related cam faces.

The control parts are coordinated so that when the cam 120 and detent disc 121 on the control shaft 93 stand so that the zero positioning of Fig. 6 engages the bar 110 and detent member 123, the pointer 106 will stand at the zero position of Fig. 3 and the lever 70 will stand parallel to the direction of platen travel to produce normal character spaces, that is, 60 spaces in a six inch line. To reproduce an unjustified line to justified length the control shaft 93 is rotated until the pointer registers with the last character of the selected line in the copy carrier. This automatically adjusts the positioning of the lever 70 to establish a character spacing such that in reproducing the line the characters will be uniformly spaced to the predetermined line length. The manual act of adjusting the machine thus requires no more of the operator than observation of the unjustified line length, and rotation of the control shaft to bring the pointer into registration with the selected line end. The exact positioning of the control is afforded by the detent mechanism. As the roller is received between the angularly spaced walls of the detent notch a fixed relationship is established which causes the lever 70 to assume a definite positioning.

The control, in addition to the operation described above, is such that an adjusted character spacing may be afforded for reproducing the characters to justified form in lines of different predetermined lengths. This last mentioned operation is effected by an axial movement of the control shaft 93 and is afforded by providing duplicated operating interconnections between the lever and the mechanism including the detent and pointer operating parts. The cam 120 and the detent disk 121 are proportioned to provide inclinations of the lever 70 such as to afford a proper character spacing for a six inch justified line. The diagrammatic illustration of Fig. 6 shows the related angular positionings of the control members for a six inch justified line. As shown, the shaft 93 also carries a cam 120' and a detent 121'. The angular positioning of the detent notches and cam faces of these members are such as to justify a four inch line, that is, a line four inches in length and containing 48 normal character spaces. Here the radial gradation of cam faces or related elevations of the cam faces is the same as for cam 120 so that as the shaft is rotated the pointer will move by normal character spaces. The angular relationship of the parts of the cam 120' and detent 121' differ from the angular positioning of the parts of the first described cam and detent by an amount sufficient to permit adjustment of the lever 70 for a four inch line. If desired, additional cam and detent pairs may be provided to increase the range of operation of the machine.

Means are provided to maintain the control shaft in the selected axial positioning. As shown, the pinion 96 and handle 95 are spaced apart on the shaft an amount greater than the spacing of the brackets 94 to permit an axial travel corresponding to the axial spacing of the cam and detent pairs. In Fig. 2 the shaft is shown in its forward positioning for justifying a six inch line. The shaft is held in this position by arranging the bar 110 and the member 10 123 so that they stand on the adjacent sides of the cam and detent pair, and by providing these parts with overlying portions 140 which prevent axial displacement of the shaft. When it is desired to change from one line length to another the bar 110 and member 123 may be moved to the right. As shown, there is a handle 141 on the bar 110, and an interconnecting mechanism between the bar and the member 123 so that both the bar and the member can be moved an amount sufficient to disengage the overlying portions 140 by one operation of the handle 141. As shown, the bar 110 carries a lateral projection 142 having an end portion 143 which interengages a slot 144 on the member 123. The relationship of the slot length and stud positioning is such that both the bar and the member may move freely throughout the normal range of travel. However, upon withdrawing the bar 110 beyond its normal range of travel it will pick up 30 the member 123 and move it to the right sufficiently to permit the shaft 93 to be moved axially for engagement of the other cam and detent pair. The pinion 96 is made sufficiently long to accommodate this axial shaft movement. 35

Suitable stop mechanism is provided for the platen to control its movement with respect to the printing position and to establish the left hand margin position of writing. If desired, the right hand margin position may also be controlled from this mechanism but as the lines are written to a predetermined length, a right hand stop is not required. As shown, the carriage 11 has rearwardly projecting lugs 146 which support a bar 147 that extends in the direction of 45 platen travel and is shown in Fig. 2 partly broken away. The bar 147 carries spaced stop members; one of which is shown at 148. Suitable means are provided for holding the stops in fixed relationship on the bar. In the illustrated embodiment of the invention the bar is arranged in the manner of the usual typewriter margin release bar, that is, it is provided with a series of notches that are spaced according to the normal character spacing, and means are provided on the stops 50 148 to engage the notches of the bar and thus be maintained in position. A stop member on the frame is provided for engagement by the stops 148. As shown, a stop is provided in the form of an upwardly extending lug 150 that is 60 fixed to the carriage supporting bar 25.

The carriage stop mechanism, the escapement, and the character space controlling mechanism are coordinated so that an aligned left hand margin of writing is afforded regardless of the adjustment of the space controlling mechanism. This is accomplished by arranging the connection between the member 71 and the lever 70 so that it traverses a line extending through the pivotal axis of the lever 70, and by proportioning 70 the parts so that in the left hand margin position the pivotal axis of the lever 70 and the axis of the roller 90 of the connecting member 71 stand in axial alignment. In this position the lever 70 may be adjusted without imparting 75

any movement to the connecting member 71. The aligned positioning is indicated by the center lines A of Fig. 2 and B of Fig. 4.

The left hand margin position is established 5 by the positioning of the stop 148. The carriage is held to the left by the escapement. The relationship of the escapement parts and the positioning of the notches on the bar 147 is coordinated between the positioning of the space controlling parts so that the left hand stop 148 may be attached to the bar 147 in a position that it will engage the stop 150 and the escapement will engage to hold the carriage and platen when the lever pivot axis and the connection axis stand 10 axially aligned.

Movement of the carriage to the left is by spring tension applied directly to the carriage. As mentioned, the carriage is held against movement by the escapement. All of the operating 20 parts between the carriage and the escapement, and including the escapement, are always under a biasing tension so that any clearance in the several parts is always taken up in the same direction. There can therefore be no operating 25 error or displacement of parts from loose connections or from the accumulated play of the several working parts.

In operating the machine unjustified copy which is to be reproduced in justified form is 30 placed in the carrier 101 so that the last character space of a line corresponding in length to the predetermined line length will stand in registration with the pointer end 107 when the spacing means is positioned to provide normal spacing. 35 That is to say, the right hand margin limit of the unjustified copy is positioned to correspond to the pointer zero position of Fig. 3 which occurs when the shaft 93 stands in the indicated zero positioning of Figs. 5 and 6. The justified line 40 length is then established by axially shifting the shaft 93; the shaft being drawn forward to justify to a six inch line or moved rearward to justify to a four inch line. The space length is then established by reference to the unjustified copy 45 and by rotating the shaft 93 to bring the pointer end into registration with the last character of a selected unjustified line as an index of the proper angular positioning for the lever 10. The selected line is then copied and is automatically spaced 50 to justified line length. Succeeding lines are copied by advancing the unjustified copy and then rotating the control shaft to index the pointer according to the selected unjustified line.

While the form of apparatus herein described 55 constitutes a preferred embodiment of the invention, it is to be understood that the invention is not limited to this precise form of apparatus, and that changes may be made therein without departing from the scope of the invention which 60 is defined in the appended claims.

What is claimed is:

1. A type character associating device of the character described comprising a platen for association of type characters in justified lines, a copy 65 holder for unjustified copy, feeding means for the platen movable by steps, an adjustably variable spacing member operatively connected between the feeding means and the platen for determining the length of a feeding step of the 70 platen, indicating means extending toward the copy holder and movable into registration with a line end of the unjustified copy, and means connecting the indicating means and the adjustably variable member and so coordinating their movements as to establish a space step such as to

justify the indicated unjustified line to a predetermined line length.

2. A type character associating device of the character described comprising a platen for association of type characters in justified lines, feeding means for the platen movable by steps, an adjustably variable spacing member operatively connected between the feeding means and the platen for determining the length of a feeding step of the platen, means for moving the adjustably variable member, comprising a rotatable control having annularly spaced detent notches spaced to provide a plurality of definite positionings of the spacing member differing from one another by an amount such as to afford one 15 whole character space difference in the justified line length, and a spring pressed member engageable in the detent notches.

3. A type character associating device of the character described comprising a platen for association of type characters in justified lines, a copy holder for unjustified copy, feeding means for the platen movable by steps, an adjustably variable spacing member operatively connected between the feeding means and the platen for determining the length of a feeding step of the platen, indicating means extending toward the copy holder and movable into registration with an unjustified line end as an index of the positioning of the adjustably variable member, means 20 connecting the indicating means and the adjustably variable member and so coordinating their movements as to establish a space step such as to justify the indicated unjustified line, and detent means to hold said indicating means and adjustably variable member in a selected one of adjusted positionings differing from one another by an amount such as to afford one whole character space difference in the predetermined line 25 length.

4. A type character associating device of the character described comprising a platen for association of type characters in justified lines, a copy holder for unjustified copy, feeding means for the platen movable by steps, an adjustably 40 variable spacing member operatively connected between the feeding means and the platen for determining the length of a feeding step of the platen, indicating means extending toward the copy holder and movable into registration with an unjustified line end as an index of the positioning of the adjustably variable member, control means for moving the indicating means and the adjustably variable member and having provision for coordinating their movements to establish 45 a space step such as to equally divide the spaces of the indicated unjustified line into the justified line length in associating the characters of the indicated line on the platen, said control means comprising a rotatable shaft having an operating 50 connection to the indicating means and to the adjustably variable member, and detent means providing stop positions of the shaft coordinated to the movement of the indicating means and the movement of the adjustably variable member to 55 establish feeding steps differing from one another by whole character spaces in the justified line length.

5. In a device of the character described for association of type characters into justified lines, 60 a movable platen, means for moving the platen by steps, means for adjusting the step movement for accommodation of different numbers of characters in lines of different predetermined length, and stop means operable as a unit and selectively 65

- effective on the adjusting means to determine the position of the adjusting means to predetermined points so coordinated with different predetermined line lengths as to distribute a desired number of characters as aliquot fractional parts of a desired line length.
6. In a device of the character described for association of type characters into justified lines, a movable platen, means for moving the platen by steps, means for adjusting the step movement for accommodation of different numbers of characters in lines of different predetermined length, a plurality of stop means selectively operable for a plurality of different line lengths and each affording stop positions of the adjusting means coordinated to a single predetermined line length for distribution of differing numbers of characters as aliquot fractions of the selected line length.
7. In a type character associating device of the character described for association of type characters in justified lines, a copy holder for unjustified copy, a movable platen, adjustably variable spacing means for moving the platen by character steps of varying length, adjusting means for the spacing means providing fixed positions of adjustment of the spacing means coordinated with the number of characters and the line length for distribution of the steps as aliquot fractions of a desired line length, and indicating means registrable with an unjustified line end as an index and movable with the adjusting means for establishing the positioning of the adjusting means by reference to an unjustified line end.
35. 8. In a type character associating device for association of characters in justified lines, a copy holder for unjustified copy, a movable platen, means for moving the platen in steps of varying length, adjusting means providing fixed positions of adjustment of the moving means coordinated with the number of characters in a line and the line length for distribution of the characters in steps that are aliquot fractions of a desired line length, indicating means comprising a pointer movable by character space steps corresponding to the spacing of unjustified copy into registration with an unjustified line end as an index of the adjusted positioning of the platen moving means, and a common operating means for coordinated movement of the indicator and space adjusting means.
9. In a type character associating device of the character described for association of type characters into justified lines, a movable platen, 55 means for moving the platen by spaces of varying length, a plurality of adjusting means of differing space length characteristics selectively operable for positioning the platen moving means and each affording a plurality of adjusted positions coordinated to a different predetermined line length, and a single control movable in one path of travel to selectively engage a desired adjusting means and movable in another path of travel for positioning the selected adjusting means.
10. In a type character associating device of the character described for association of type characters into justified lines, a movable platen, means for moving the platen by spaces of varying length, a plurality of adjusting means comprising axially related members of annular form and of differing space length characteristics selectively operable for positioning the platen moving means and each affording a plurality of adjusted positions coordinated to a different pre-
- determined line length, and a single control connected to the adjusting means and axially movable for selective engagement of a desired annular member and rotatably movable for adjustably positioning the selected annular member.
11. In a device of the character described for association of type characters into justified lines, a platen for association of the characters, means for moving the platen by character space steps, means for varying the length of the character space step movement comprising an adjustable member, an axially movable and rotatable shaft connected to said adjustable member for adjustment thereof by rotation of said shaft, detent means comprising a plurality of detent members axially spaced on the shaft and selectively operable to provide predetermined positionings for said adjustable member, said detent members each affording a plurality of related positionings coordinated to a different predetermined line length, and means for selectively engaging a detent member.
12. In a device of the character described for association of type characters into justified lines, a frame, a platen for association of the characters, means for supporting the platen for movement with respect to the frame, means for moving the platen by character space steps, means for varying the length of a character space movement comprising an adjustable member, an axially movable and rotatable shaft connected to the said adjustable member for adjustment thereof by rotation of said shaft, means for indicating the positioning of the adjustable member, detent means comprising a plurality of detent members axially spaced on the shaft and selectively operable to provide predetermined positionings for the adjustable member coordinated with respect to the number of character spaces in a predetermined line length, said detent members each affording a plurality of related positionings coordinated to a different predetermined line length, and means on the shaft coordinated in positioning to the detent means for operation of the indicating means, said shaft being adapted for manual movement longitudinally of its axis for selective coaction with a desired detent means and engagement with a coordinated operating connection to the indicating means.
13. In a device of the character described for association of type characters into justified lines, a platen for association of the characters, means for moving the platen by character space steps, means for varying the length of a character space step comprising an adjustable member, a rotatable shaft connected to said member for rotation by said shaft, said shaft having a plurality of related pairs of cams and detent means, an indicator movable to indicate the positioning of the adjustable member and adapted for actuation by a cam, a detent member adapted for engagement with a detent means to hold the detent means in fixed positioning, each cam and detent pair affording coordinated positionings for the indicating means and the adjustable member for varying the space length adjustment in predetermined amounts for a predetermined line length, and operating means for selectively engaging a cam and detent pair with said indicator and detent member respectively.
14. In a device of the character described for association of type characters in justified lines within predetermined margin limits, a carrier for unjustified copy, a frame, a platen for association of characters, means for supporting the platen

- for movement with respect to the frame, means for moving the platen by steps, means for varying the extent of a step movement comprising an adjustable guide member pivotally supported on the frame, mechanism operably attaching the platen supporting means to the adjustable guide member including a connection movable along said guide member and located at the pivot axis of the adjustable guide member where said mechanism is at a margin position, said relationship of parts constituting a margin position wherein the adjustable guide member may be adjusted without imparting movement to said mechanism, and means for adjusting the adjustable member incorporating means registerable with the end of a selected line of unjustified copy as an index of the adjusted positioning of the adjustable member for reproduction of a line to justified length.
15. In a device for associating type characters into justified lines from a like association of characters in unjustified lines, a holder for unjustified copy, a platen, an adjustably variable spacing member therefor, control means for varying the adjustment of said spacing member to vary the length of a platen step, and means operable with said control means for registering with an unjustified line end of unjustified copy on the holder to automatically adjust said spacing member for space steps such as to reproduce the lines to justified length.
16. In a type character associating device of the character described for associating type characters in justified lines, a copy holder for unjustified copy, a movable platen, adjustably variable spacing means for moving the platen by character steps of varying length, adjusting means for the spacing means providing fixed positions of adjustment of the spacing means coordinated with the number of characters in a line and the line length for distribution of the characters in steps differing by one whole character space in the desired line length, and indicating means registerable with an unjustified line end of unjustified copy on the holder and having an operating connection with said adjusting means for establishing the positioning of the adjusting means to reproduce the indicated line to justified length.
17. In a device of the character described for associating type characters into justified lines, a movable platen, adjustably variable spacing means for the platen, stop means to position the spacing means at predetermined points coordinated to different justified line lengths and the number of characters in a line and comprising related groups of stops, one group for each line length, the stops of each group being coordinated for a particular line length, and a control member for selecting a desired stop group and for selecting the stop of the desired stop group.
18. In a device of the character described for associating type characters into justified lines, a carrier for unjustified copy, a movable platen, adjustably variable spacing means for the platen, stop means to position the spacing means at predetermined points coordinated to the different line lengths and the number of characters in a line and comprising related groups of stops of which the stops of each group are coordinated to a single line length, a control selectively movable to a desired stop group and for moving the selected group to select a particular stop, and means movable by the control into registration with a line end of the unjustified copy as an index of adjustment of the control to position the spacing for reproduction of the indicated line to justified length.
19. In a device of the character described for association of type characters into justified lines, a movable platen, means for moving the platen by steps, means for varying the extent of step movement comprising an angularly adjustable member located adjacent to and below the normal position of said platen and supported for movement on a horizontal axis which extends transversely with respect to the line of movement of the platen, said member having a guideway thereon, a connecting member pivotally supported on the platen and having an operating attachment to the platen moving means and to said guideway, the guideway attachment being such that the effective connection thereto in the margin position of the connecting member coincides with the pivot axis of the angularly adjustable member whereby the adjustable member may be adjusted in the margin position without imparting movement to the connecting member and platen, and stop means determining several positions of adjustment of said angularly adjustable member coordinated with the number of characters in a line and the line length for distribution of the characters in steps differing by one whole character space in the desired line length.
20. In a device of the character described for association of type characters into justified lines, a platen, movable supporting means therefor, an escapement, variable spacing means operatively connected to the platen supporting means, and rack means providing an operative connection between the variable spacing means and the escapement comprising a rack in meshing engagement with the variable spacing means and supported for movement on the platen supporting means in the direction of platen travel, a second rack normally engaging the escapement and operatively connected for movement with respect to the first rack in a direction transverse to the line of movement of the first rack and movable from its normal position to disengage the escapement for rapid traverse of the platen while meshing engagement of the first rack with the variable spacing means is maintained.

EDWARD C. WELLS.
